UNITED STATES PATENT OFFICE.

SAMUEL W. HYATT, OF CONNERSVILLE, INDIANA, ASSIGNOR TO INDIANA LAMP CORPORATION, OF CONNERSVILLE, INDIANA, A CORPORATION.

LAMP FOCUSING AND ADJUSTING DEVICE.

Application filed January 28, 1927. Serial No. 164,191.

This invention relates to a focusing and tilting control for headlights.

The chief object of this invention is to provide a multiple control for focusing and tilting which is simple in character and which will not be disturbed from the adjusted position by vibration and the like.

The chief feature of the invention consists in the provision of a socket support in the form of a yoke and a lever associated therewith for tilting the same, said yoke being tiltable and movable to and fro for focusing by a pair of bolts in substantially parallel relation.

Another feature of the invention consists in the formation of the yoke with wings which are slidable longitudinally and transversely of the elongated slots formed as extensions of an elongated elliptical opening in the reflector receiving the socket and yoke.

The full nature of the invention will be understood from the accompanying drawings and the following description and claims:

Fig. 1 is a central sectional view of a portion of a headlight with parts shown in elevation and in the upward tilted position. Fig. 2 is a view similar thereto but with the parts in the lowered or depressed tilted position. Fig. 3 is a transverse section taken on line 3—3 of Fig. 1 and in the direction of the arrows.

In the drawings, 10 indicates a suitable casing and 11 a reflector enveloped thereby. A light bulb 12 is detachably mounted in the connecting plug or socket 13 and is in electrical connection thereby with the current conducting wires 14. The foregoing consists in the usual or conventional lamp construction including other parts not shown.

A yoke 15 is suitably secured as by sweating or the like, to the socket 13 and said yoke includes a transverse rear portion 16 apertured and threaded as at 17. The casing is provided with a similarly aligned opening 18 and the casing is countersunk as at 19 adjacent thereto to receive the slotted head 20 of a bolt having the threaded portion 21 and the non-threaded portion 22. The threaded portion 21 is mounted in the threaded opening 17 of the yoke. Rotation of the bolt from without the casing secures axial movement of the socket 13 through the yoke 15, said yoke being prevented from rotating as follows:

The ends of the yoke are turned outwardly

or laterally as at 23 and each lateral extension is again turned angularly so as to lie parallel with the body portion 15 as at 24. The extensions 23 and 24 form wings receivable by elongated diametrical slots 25 formed in the reflector and formed as continuations upon opposite sides of an elongated slot or opening 26, the same having a width at least equal to the socket 13. The elongated rearward extensions 24 thus prevent rotative movement of the yoke for all positions of the yoke and thus the yoke may be moved axially to and fro without rotative movement being imparted thereto.

The means for tilting the socket 13 is herein shown as including an angular lever having one end 30 fulcrumed upon the casing immediately adjacent the slightly enlarged opening 18 and having its opposite end 31 apertured and threaded to receive a bolt 32 positioned parallel to bolt 22 and in substantially the same formation, that is, having an exposed portion without the casing for external manipulation. The lever intermediate the ends 30 and 31 is substantially U-shaped as 33 and is apertured as at 34 and 35 so as to rotatably support bolt 22. Thus, threading movement of bolt 22 has no effect on the lever. A spring 36 is interposed between the casing and the lever end 31 and normally bears forwardly thereon. Another spring 37 normally bears on the mid-portion 16 of the yoke and also bears upon the lever intermediate its ends to insure bearing of the lever on the casing at the fulcrum. Both springs 36 and 37 are concentric with their respective supporting bolts and both bolts are herein shown provided on their inner ends with angular enlargements 40 to prevent undue unthreading movement.

The operation is as follows: Rotation of bolt 22 secures no tilting action of the light bulb or socket 13, but merely focuses the same in the reflector, the movement being parallel to the axis of the reflector as shown herein. Threading movement of the bolt 32 causes tilting movement of the lever which by reason of the multiple contact or engagement 34—35 with the bolt 22, secures similar tilting movement of the yoke and therefore the light and socket therewith. The multiple engagement prevents rotation of the lever when bolt 32 is rotated since the yoke cannot rotate by reason of the wings 24 lying in the elongated slots 25. Figure 1 shows the spring 36 com-

pressed and the lever tilted upwardly with the yoke arranged in the upward position. Figure 2 shows spring 36 relatively expanded and the lever tilted downwardly with the result that the yoke is positioned in its lowermost tilted position, the fulcrum of the lever being coincident with the bearing on the casing where bolt 22 passes through the same. The two bolts 32 and 22 are substantially parallel to each other and the pivotal axis of the lever 33 is substantially transverse to and intersects the focusing axis including the bolt 22.

The invention claimed is:

- 15 1. In combination in a lamp having a light bulb support and a casing, a reflector therein with an elongated centrally positioned slot through which said light bulb support projects, said slot having oppositely directed aligned extensions, a U-shaped light bulb support supporting strap, said support being secured at the free end of said strap, said strap having a threaded central aperture and a pair of laterally and outwardly directed arms seatable in said slot extensions and longitudinally and transversely movable therein, and a rotatable swivelably mounted member having a tool engageable casing exposed portion and an opposite threaded portion for central

aperture threaded engagement, another member similar to the first mentioned member and similarly mounted upon said casing and in adjacent and substantially parallel relation thereto, and an angular lever having multiple anchorage on said first mentioned member and threaded engagement with the second mentioned member whereby rotation of the latter secures cocking of the former and rotation of the former member secures adjustment of the arms in said extensions and 40 the strap with the light bulb support in said elongated slot.

2. A device as defined by claim 1, characterized by the addition of yielding means between the lever and casing and other yielding means between the lever and the U-shaped strap.

3. A device as defined by claim 1, characterized by the addition of yielding means between the lever and casing and other yielding means between the lever and U-shaped strap, said yielding means being supported by the rotatable members and being concentric therewith.

In witness whereof, I have hereunto affixed 55 my signature.

SAMUEL W. HYATT.
